US0D1026059S

(12) **United States Design Patent** (10) Patent No.: **US D1,026,059 S**
(45) Date of Patent: ** May 7, 2024

(54) **ROBOTIC ARM**

(71) Applicant: **Shenzhen Yuejiang Technology Co., Ltd.**, Guangdong (CN)
(72) Inventors: **Zhufu Liu**, Guangzhou (CN); **Mengyan Hu**, Guangzhou (CN); **Peichao Liu**, Guangzhou (CN); **Junjie Xie**, Guangzhou (CN)

(**) Term: **15 Years**

(21) Appl. No.: **29/880,471**

(22) Filed: **Jul. 24, 2023**

Related U.S. Application Data

Assistant Examiner — Mark T. Philippss

(57) **CLAIM**

The ornamental design for a robotic arm, as shown and described.

DESCRIPTION

FIG. 1 is a front, top perspective view of a robotic arm, showing our new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the robotic arm that form no part of the claimed design.

1 Claim, 8 Drawing Sheets
